UNITED STATES PATENT OFFICE.

HUGH ROSS, OF SHEBOYGAN, WISCONSIN.

GAUNTLET.

1,315,421.

Specification of Letters Patent.

Patented Sept. 9, 1919.

Application filed July 23, 1917. Serial No. 182,100.

To all whom it may concern:

Be it known that I, HUGH Ross, a citizen of the United States, and resident of Sheboygan, in the county of Sheboygan and 5 State of Wisconsin, have invented certain new and useful Improvements in Gauntlets, of which the following is a specification.

This invention relates to gauntlets.

One of the objects of the invention is to 10 improve the cuffs of gauntlets to make the same easier to wear and to be capable of liberating themselves when caught on any object.

Another object is to increase the flexibility of a gauntlet particularly around the wrist portions to render it easy to put the same on and take it off and at the same time maintain a relatively snug fit of the gauntlet about the wrist.

20 Another object is to provide a novel gauntlet adapted to meet the various requirements for commercial use.

These and other objects are accomplished by providing a gauntlet having a cuff including two spaced members, separate web members inserted between said spaced members to give flexibility to the gauntlet, and means adjacent the web members to increase the snugness of the gauntlet around the 30 wrist.

The invention is illustrated on the accompanying sheet of drawings, in which,

Figure 1 is a view of the back of a gauntlet embodying my invention;

35 Fig. 2 is a transverse sectional view of the same taken in the plane of line 2—2 of Fig. 1;

Fig. 3 is a fragmentary sectional view showing a web member between the spaced 40 cuff members, and also the elastic means for increasing the snugness around the wrist;

Figs. 4 and 5 show respectively a piece of leather which forms a casing, and the elastic member which is inclosed by the casing, and,

Fig. 6 shows the preferred shape of each of the web members.

The various novel features of my invention will be apparent from the following 50 description and drawings, and will be particularly pointed out in the appended claims.

Referring to the figures of the drawing, my gauntlet 10 is provided with a cuff including two separate substantially parallel 55 members 11 and 12 spaced from each other, said members being either stiff or flexible

and preferably flexible to a limited degree. The rear corner portions of these members 11 and 12 are rounded and have edges 13 and 14 which converge toward the fingers 60 of the gauntlet, the forward corner portions of the cuff members 11 and 12 also being rounded. These spaced cuff members 11 and 12 are respectively sewed to the front and back portions of the body of the gauntlet, it being noted that the rear portions of the front and back portions of the gauntlet are left open at the sides thereof for the reception of the forward V-shaped portions 65 15 of web members 16 which flexibly connect the cuff members 11 and 12 at the sides of the cuff. It will be noted that each of the web members 16 preferably has its widest portion 17 intermediate the ends thereof, said widest portion 17 of the web 70 75 members being secured to the spaced cuff members 11 and 12 and to the front and back of the gauntlet at a point adjacent to the wrist portion of the gauntlet, this being for the purpose of giving a considerable 75 degree of flexibility to the gauntlet at the wrist portion thereof to render it easy to put the gauntlet on and take it off of the hand.

As mentioned hereinabove, the forward V. 85 shaped part of each of the flexible web members occupies a corresponding opening left between the front and back of the gauntlet at the sides thereof. The flexible web members are applied to the body of the gauntlet 90 and to the cuff members thereof by sewing the same in any approved manner.

There is a distinct advantage in having the spaced cuff members 11 and 12 connected at the sides by the flexible web members. 95 Not only do the flexible web members give great flexibility to the gauntlet to facilitate applying and withdrawing the same, but also if the cuff members become caught on any object said cuff members are readily 100 liberated. This is not true of a cuff made up in a single piece whether or not it is connected at one portion thereof by a single flexible web.

In addition to having the gauntlet flexible, especially at the wrist portion to facilitate the application and withdrawal of the gauntlet, it is highly desirable normally to have the gauntlet snug about the wrist of the hand when the gauntlet is applied. To this 110 end I have provided means 18 preferably secured to the body of the gauntlet adjacent

the cuff members 11 and 12 and also preferably adjacent the widest portions 17 of the flexible members 16. This means includes an elastic member 19, shown in Fig. 5, and a casing 20, preferably of flexible leather.

By referring to Figs. 4 and 5, it will be noted that when the elastic 19 is in its normal relaxed condition, it is considerably shorter than its casing member 20. In making this flexible means 18 and applying the same to the gauntlet, the elastic member 19 is first stretched to the length of the casing member 20 and held in such stretched condition until the casing member 20 incloses the same and the ends of the elastic member 19 and its casing member 20 are sewed to the body portion of the gauntlet, as shown particularly in Fig. 1 of the drawings. After the elastic means 18 is applied to the gauntlet and the elastic 19 is permitted to contract to its normal condition, it is noted that the casing 20 is gathered and gives an attractive appearance to the strap. The casing 20 also acts as a limit to the stretching effect of the elastic member 19.

As shown in Fig. 1 of the drawings, the elastic means 18 extends across the back of the gauntlet and is secured to the front portion of the gauntlet adjacent the widest portion 17 of the flexible web members 16. This is the preferable arrangement. When the gauntlet is not on the hand the web members 16 will fold on a longitudinally center line thereof permitting the cuff members

11 and 12 to come in contact with each other, and the body of the gauntlet may be wrapped around the cuff making a flat package to occupy a minimum amount of space and readily receivable by a pocket without giving the latter a bulged appearance.

It is apparent that there may be various modifications of my invention as herein particularly shown and described and it is my intention to cover all such modifications which do not involve a departure from the spirit and scope of the invention as set forth in the following claims.

I claim:

1. A gauntlet having a cuff including two spaced members, a web member inserted between said spaced members and having its widest portion near its middle to give flexibility at the wrist portion of the gauntlet, and means normally to increase the snugness of the gauntlet around the wrist.

2. A gauntlet having a cuff including a plurality of spaced members, web members inserted between said spaced members and having their widest portions near the middle thereof and near the wrist portion of the gauntlet, and yieldable means connected adjacent the wrist portion of the gauntlet to normally increase the snugness of the same about the wrist.

Signed at Sheboygan, State of Wisconsin, this 18 day of July, 1917.

HUGH ROSS.
